Primary Examiner — Karen E Eldridge Powers*(74) Attorney, Agent, or Firm* — Vladimir Postnikov(57) **CLAIM**

The ornamental design for a cleaning brush, as shown and described.

DESCRIPTION

FIG. 1 is a left-side elevation view of a cleaning brush showing the new design;

FIG. 2 is a right-side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a front, top and left-side perspective view thereof;

FIG. 8 is a rear, bottom and right-side perspective view thereof;

FIG. 9 is an enlarged view of the encircled portion in FIG. 1; and,

FIG. 10 is an enlarged view of the encircled portion in FIG. 7.

The broken lines depict portions of the article that form no part of the claimed design.

1 Claim, 10 Drawing Sheets(56)
